UNITED STATES PATENT OFFICE.

CHARLES LEON LIBBY, OF BRIDGEPORT, CONNECTICUT, ASSIGNOR TO
EDWARD P. BULLARD, OF SAME PLACE.

TURRET-LATHE.

SPECIFICATION forming part of Letters Patent No. 406,413, dated July 2, 1889.

Application filed February 16, 1889. Serial No. 300,133. (No model.)

To all whom it may concern:

Be it known that I, CHARLES LEON LIBBY, a citizen of the United States, residing at Bridgeport, in the county of Fairfield and State of Connecticut, have invented certain new and useful Improvements in Turret-Lathes; and I do hereby declare the following to be a full, clear, and exact description of the invention, such as will enable others skilled in the art to which it appertains to make and use the same.

My invention relates to certain new and useful improvements in turret-lathes, but more particularly to the turret and the reciprocating carriage upon which said turret is mounted and adapted to rotate, and to certain means for releasing, turning, and locking said turret and for governing the movement of the carriage.

Heretofore in turret-lathes it has been necessary that the carriage should make its full backward stroke before revolving, and this whether operating upon long or short work. It is therefore the object of my invention, first, to provide means whereby the length of travel of the carriage and the point of revolution of the turret may be predetermined; second, to furnish, in connection with the variable-stroke feature, simple and effective devices for unlocking, rotating, and locking the turret at the end of its backward movement, so that a new tool may be brought into line with the chuck and there retained, and, third, to afford means whereby the rotating mechanism, if desired, may be restrained from operation, so that one tool is continuously employed; and with these ends in view my invention consists in the construction and arrangement of the co-operating mechanical elements, whereby the objects hereinbefore set forth are attained.

In order that those skilled in the art to which my invention appertains may more fully understand my improved machine, I will describe the same in detail, reference being had to the accompanying drawings, which form a part of this specification, and in which—

Figure 1 is a plan view of the carriage and turret; Fig. 2, a rear end elevation; Fig. 3, a

longitudinal section at the line xx of Fig. 1; Fig. 4, a detail transverse section through the turret, carriage, and ways; Fig. 5, a detail plan showing the unlocking device; Fig. 6, a detail side elevation of the same; Fig. 7, a rear side elevation showing the automatic feed for the carriage.

Similar reference-numbers denote the same parts in all the figures of the drawings.

1 is the frame of the machine, which upon one end (not shown) may have any suitable revoluble head and chuck and such other parts as are necessary for a complete lathe. Upon the other end of said lathe are formed ways 2, upon which a movable base 3 is mounted, and may be adjusted toward and from the chuck, so that work of various lengths may be accommodated. The adjustment of the bed-piece is effected by means of downwardly-projecting bracket 40, having 6c therein (see Figs. 1 and 2) a journaled pinion 41, having an actuating-crank 42. The pinion meshes with a rack 43 on the under side of the frame. By turning this crank the bed may be moved upon its ways. Upon ways 4, which are formed upon this bed-piece, is mounted the turret-carriage 5.

6 is the turret, preferably hexagonal in shape and provided with a tool-holding aperture 7 in each of its faces. Said turret is pivoted and adapted to rotate upon a central vertical shaft 8. In the bottom face of the turret is a series of locking-recesses 9, one beneath each tool-holding aperture, and projecting downward from said bottom face into an annular recess in the top of the carriage are studs 10, each of which is preferentially furnished with a roll or collar 11 upon its extremity.

A rack 12 extends longitudinally of the turret-carriage, and is engaged by a pinion 12a upon a transverse shaft 13, which is journaled in the base, and has upon one end a hand-wheel 14, whereby the shaft may be revolved and the carriage caused to travel forward or backward. The carriage may, however, be caused to feed automatically by means of mechanism which, though forming no essential part of my present invention, I will now describe. 33 is a shaft extended along the

side of the machine and driven from any suitable source of power, as a belt and pulley. Upon a bracket 34, depending from the carriage, is a sleeve and gear 35, turning in said bracket and splined to the shaft 33. This gear, as will be readily understood, will receive rotary motion from the shaft, and may also move longitudinally thereon. It engages a gear 36 on a short shaft 37, also mounted in the bracket, and the shaft 37 carries on its end a spiral pinion 15. This pinion actuates a spur-gear 38, journaled in the bracket, and a pinion on said spur-gear turns a gear 39, which is fast upon the transverse shaft 13. 15 By the means heretofore set forth, and which are particularly shown at Fig. 7, the travel of the carriage may be effected without the use of the hand-wheel.

Mounted in the carriage beneath the turret is a locking-bolt 16, whose end is conformed to the locking-recesses in the turret, and is adapted normally to be engaged with one of them. (See Figs. 3 and 4.) This bolt is mounted in a socket 17, and is upheld by a 25 spring 18. It has upon either side trunnions 19, which project outwardly through slots in the socket.

In the central line of the carriage, and sliding upon ways in the base, is a block 20, which 30 at its lower end is threaded upon a screw 21, whereby it may be moved along its ways nearer to or farther from the end of the bed. In a recess in this block is hinged, as upon a pin 22, a yoke 23, which is normally retained 35 in the position shown at Fig. 6 by a spring, as 24. This yoke has at its top portion two inwardly-projecting flanges 25, wedge-shaped in longitudinal section. (See Figs. 4, 5, and 6.) The purpose of this yoke and the wedge-shaped 40 flanges thereon is to withdraw the locking-bolt, as will hereinafter appear. Upon the block 20, a little ahead of the yoke just described and in line with one of the downwardly-projecting studs on the turret, (see 45 Fig. 4,) is a pawl 26, pivoted to said block. It cannot turn past the perpendicular in one direction by reason of its abutment against the block, but in the other it may turn down against the pull of the spring 27.

50 In the top of the carriage, beneath the turret, is a slot 28, cut through into the annular groove in which the studs on the turret travel, and this slot is in line with the pawl just described, so that when the slot comes over the pawl the latter may be raised by its spring, so that its point will enter therein and engage one of the studs, as hereinafter will be explained.

29 is a cover-plate arranged to slide longitudinally just beneath the floor of the carriage and to cover or uncover the slot 28 with its end, as may be required, so that the pawl may freely enter the slot or may be debarred entirely. This cover-plate is actuated by a 65 small lever 30 at the rear end of the carriage, and said lever is provided with any suitable detent or locking device, as a spring-

actuated bolt engaging a notched plate 31, which serves to retain the plate in either position over the slot or clear of it.

The operation of my machine is as follows: 70 The carriage is moved forward until the tool in operative position has acted upon the work, and the carriage is then reversed and drawn backward by the hand-wheel. When 75 it has receded a sufficient distance to allow the tool to properly clear the work, the trunnions on the locking-bolt slide under the wedge-shaped flanges of the yoke, and said bolt, as the carriage recedes still farther, is 80 by said flanges withdrawn out of the locking-recess in which it has been engaged, and the turret is thereby left free to turn upon its axis. At the moment of the complete withdrawal of the locking-bolt the pawl has 85

come opposite the slot which opens into the annular recess in the carriage, and its end has been lifted into said recess by the spring. Said end then engages one of the roller-headed studs, and by the still further backward movement of the carriage turns the carriage one-sixth of a revolution by means of said stud. When this turning is completed, the locking-bolt trunnions having meanwhile passed the wedges on the yoke, the locking-bolt 95 is raised by its spring into engagement with the next locking-recess. When the carriage is moved forward again, the trunnions, engaging the upper faces of the wedge-shaped projections upon the yoke, ride over the same freely 100 without withdrawal, the yoke meanwhile turning downward upon its hinge and against its spring. The turret-pawl also is turned down against the pull of its spring, and the carriage rides freely over it during all of its 105 backward movement and for a portion of its forward movement until the slot in the carriage again comes over the pawl, when the latter is raised into said slot to turn the turret. 110

When operating the turret for the use of successive tools, as above stated, the sliding cover-plate is entirely withdrawn from over the slot in which the turning-pawl acts. If, however, it is desired to use one face only of the turret and to use that face over and over again, the cover-plate is, by means of its lever, projected forward, so as to cover the slot. In that case the pawl is prevented from entering the slot and is continuously retained turned downward against its spring, and the locking-bolt, while withdrawn from engagement by the wedges at each backward movement of the carriage, springs back into the same recess as soon as it has passed the 125 hinged yoke.

By means of its screw the block on which the pawl and the yoke are mounted may be moved along relative to the base, so that the turret may be unlocked and turned at any 130 desired distance from the forward limit of movement of the carriage.

I claim—

1. The combination, in a machine of the

character described, with the base, the carriage, means for moving the same, and the revoluble turret mounted thereon, of the locking-bolt engaging said turret, the movable block arranged beneath said carriage, a hinged wedge mounted upon said block in the path of said locking-bolt, and a pawl hinged upon said block and adapted to engage and turn the said turret, substantially as specified.

2. The combination, in a machine of the character described, with the base having ways formed therein, of the carriage mounted on the ways and means for moving it thereon, the rotatable turret upon said carriage, studs projecting downward from the turret, a spring-actuated locking-bolt arranged in the carriage and adapted to engage recesses in the turret, the block beneath the carriage, and wedges arranged thereon in the path of the locking-bolt, and a spring-actuated pawl arranged in the plane of the studs on the turret and adapted to engage therewith, whereby the locking-bolt may be withdrawn 25 and the turret turned, substantially as set forth.

3. The combination, with the bed, the carriage, the turret mounted and adapted to turn thereon, and the locking-bolt, of the block 30 mounted in ways beneath the carriage, a screw for varying the position of said block lengthwise of the machine, the yoke hinged upon said block and provided with wedges

located in the path of the locking-bolt, the spring-actuated pawl pivoted upon the block 25 just forward of the yoke, and the studs upon the turret, wherewith the said pawl is adapted to engage in rotation, substantially as set forth.

4. The combination, with the turret and the 40 studs upon the lower surface thereof, of the pawl pivoted to a stationary part of the lathe and adapted to engage and turn the studs *seriatim*, the sliding carriage supporting the turret and having a slot through which the 45 pawl is raised into engagement with the studs, and a sliding plate and means for actuating the same, whereby the slot may be opened for the reception of the pawl or closed as against entrance of the same, substantially as specified.

5. In a machine of the character described, the combination, with the base and carriage, of the turret, its studs and the locking-bolt, the movable block, the means thereon for 55 withdrawing the locking-bolt, the pawl whereby the studs may be engaged, and the cover-plate and means for moving the same over or away from the slot in the carriage beneath the studs, substantially as specified.

In testimony whereof I affix my signature in presence of two witnesses.
